UNITED STATES PATENT OFFICE

2,561,704

TONGS

Ervin C. Ladewski, La Porte, Ind.

Application November 8, 1948, Serial No. 58,985

1 Claim. (Cl. 294—104)

1

This invention relates to a device in the nature of a tongs, having gripping jaws adapted to grasp and support an article.

The primary object of the invention is to provide a device of the character described that will be novelly designed in a manner to grip articles tightly, so that said articles can be transported, or otherwise handled with considerable facility.

Another important object is to provide a device of the character described which will be of rugged construction, relatively light considering the weight of the articles which it is adapted to support, and capable of simple and speedy operation.

Another important object is to provide a device of the character described in which the jaws can be locked in open position during maneuvering of the device for the purpose of grasping an article, and wherein, on release of the jaws for the purpose of gripping said article, said jaws will automatically engage the article tightly.

Another important object is to provide a device of the character stated adapted for one hand manipulation, so that the user may have his other hand free for supporting himself, manipulating the article to be grasped, or for other purposes.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings

Figure 1 is an elevational view of a tongs constructed in accordance with the invention.

Figure 2 is a view taken from the right of Fig. 1, the dotted lines indicating a second position of the movable jaw.

Figure 3 is an enlarged fragmentary view, partly in elevation and partly in longitudinal section, through the upper end of the device.

Figure 4 is an enlarged section taken substantially on line 4—4 of Fig. 1.

Figure 5 is a section taken substantially on line 5—5 of Fig. 3.

Figure 6 is a section taken on line 6—6 of Fig. 4.

Referring to the drawings in detail, 10 is an outer tubular member which can be of any length desired, said member being formed at its lower end with external threads 11, and being rigid at its other end with the handle 12.

Telescoped in the outer tubular member 10 is the inner tubular member 13, having at one end

2

the handle 14. As readily seen from Fig. 1, handles 12 and 14 are so formed, and disposed at a predetermined distance apart, as to permit their being readily grasped in one hand, and brought together by a squeezing action.

By squeezing the handles 12 and 14, the inner member is telescoped in the outer member, from its normally withdrawn position. During relative movement of the members, it is desirable that 10 guide means be provided adapted to prevent relative rotation therebetween, and to this end, I provide a cross pin 15 extending across the members, said pin 15 being anchored in the wall of the outer tubular member 10, and passing through diametrically opposed longitudinal slots 16 and 17 formed in the inner tubular member. Slots 16 and 17 are bayonet slots, having at their upper ends the oppositely directed slot extensions 18, 19.

By reason of this construction, it can be seen that during relative movement of the members 20 longitudinally of each other, the pin 15 provides a guide preventing relative rotation, and additionally, said pin engaging opposite ends of the slots 16 and 17, constitutes a stop limiting longitudinal movement in opposite directions. Additionally, when pin 15 is at the upper end of slots 16 and 17, that is, when the handles 12 and 14 have been fully brought into substantial engagement with each other, by rotating handle 14, or for that matter either handle relative to the other, through a small part of a single rotation, the cross pin 15 moves into the oppositely directed slot extensions 18 and 19, and accordingly the handles can be released and will be locked against relative longitudinal movement while the pin is engaged in said slot extensions.

At its inner end, the inner tubular member 13 is reduced as at 20, to provide clearance at diametrically opposed sides of the inner tubular member for the ends of a cross plate 21, that 40 extends through the diametrically opposed longitudinal slots 22 formed in said reduced extension 20.

Said plate 21 extends through eye 23 formed on the inner end of an elongated connecting rod 45 24. Said connecting rod 24 is thus secured to the inner tubular member 13 in a manner to prevent relative longitudinal movement therebetween, while at the same time permitting a certain amount of looseness in the connection to permit some lateral movement of the connecting rod relative to the member 13.

The inner member 13 is normally held retracted or withdrawn relative to the outer tubular member, in the position illustrated in Figs. 1 to 3 inclusive and I provide for this by providing a ring

or flange 25 engaging the inner end of the tubular member 13, said ring engaging one end of a coil spring 26 that engages at its other end the ring 27 seated on the annular shoulder 28 formed in the outer tubular member 10. As a result, said spring, tending to expand, will normally retain the members in the position illustrated. However, against the action of the spring, the handles 12 and 14 can be squeezed or compressed, so as to telescope member 13 within the outer member. When the member 13 has been telescoped against the spring action to its full limit as determined by the length of the slots 16 and 17, partial rotation of the inner tubular member 13 as described hereinbefore causes pin 15 to move into the slot extensions 18 and 19, so as to hold the members telescoped against the spring action.

Referring now to Fig. 4, an internally threaded sleeve 29 is threaded upon the lower end of the outer tubular member 10, and the connection is secured by means of a screw 30. Welded or otherwise fixedly secured to the sleeve 29 is the center portion of the cross member or plate 31, that is U-shaped in cross section, and which at one end straddles the inner end or tongue 32 of a fixed jaw generally designated 33, that extends obliquely from its fixed connection to the end of the cross member 31, terminating at its free end substantially in line with the longitudinal axes of the tubular handle members. Straddling said plate and tongue is the bifurcated end 34 of a reinforcing member 35, and rivets 36 or similar securing means hold said reinforcing member, plate, and jaw rigidly assembled.

Formed on the lower end of the connecting rod 24 is an eye 37, having relatively loose engagement with the hook 38 formed on the inner end of the movable jaw generally designated 39. Said movable jaw 39 is approximately L-shaped, and is fulcrumed intermediate its ends on a pivot bolt 40 extending transversely of the other end of the plate 31. So far as its gripping end is concerned, the jaw 39 is formed like the jaw 33, and also like the jaw 33, is extended downwardly from an end of the plate 31 obliquely relative to the tubular handle members. The free end of the jaw 39 terminates in line with the longitudinal axes of the handle members, in engagement with the free end of the jaw 33. The gripping portions of the jaws thus are of like appearance and are in symmetrically balanced opposition.

Referring now to the particular construction illustrated for each of the jaws, the fixed jaw 33 can be integrally stamped or otherwise formed from a sheet of material to provide an outer longitudinally extended reinforcing rib 41, that merges into the shovel-like jaw member 42, the peripheral edge of which is inturned and formed with teeth 43.

Referring to the jaw 39, this also is formed from a sheet of material to provide the flat shovel-like jaw member 44, formed integral with the reinforcing rib 45, the peripheral edge of said jaw member 44 being inturned as best shown in Fig. 6, and formed with teeth 46.

The use of the invention may now be noted. The structure has ready applicability to a great many uses, such as the removal of overhead electric bulbs, and of course it will be understood that for this particular function, the jaws should be formed in a manner to retain said bulbs after removal, and to prevent breakage of said bulbs.

Additionally, the device is adapted for the removal of articles from narrow or otherwise confined locations, can be used for the feeding of caged animals, the removal of clinkers from furnaces, and the handling of other articles. In this connection, it has been found in actual use that by the correct operation of the tool, weights of as much as two-hundred pounds or more can be gripped and carried therewith.

In operation, the user squeezes handles 12 and 14, and this has the effect of swinging movable jaw 39 to the dotted line position illustrated in Fig. 2. When the jaw has been swung outwardly in this manner, it can be retained in its outwardly swung position by entry of the cross pin 15 into the lateral slot extensions 18 and 19. Then, when it is desired to seize the article, the handle 14 is retracted more or less slowly, under the control of the operator, so that the jaws engage the article to be gripped. By reason of the inclination of the teeth, retrograde movement of said article, out of engagement with the jaws, is effectively prevented.

What is claimed is.

1. A device of the class described including an elongated outer tubular member; an elongated inner tubular member slidable within the outer member; handles on the inner and outer members adapted to be squeezed for telescoping of said inner member in the outer member; yielding means engaging the inner member and adapted to hold the handles normally spread apart; a plate fixedly secured at its center to the outer member and disposed directly crosswise of said members, the ends of said plate projecting laterally in opposite directions from said members; a jaw fixedly connected at one end to one end of the plate, said jaw being of shovel-like formation with serrated side edges and being extended obliquely relatively to the tubular members from its connection to the plate and terminating substantially in line with the longitudinal axes of said tubular members; an L-shaped jaw fulcrumed intermediate its ends upon the other end of said plate, one end of said L-shaped jaw directly underlying the center of the plate; a connecting rod extending between said end of the L-shaped jaw and the inner member for movement of the L-shaped jaw responsive to telescoping of the inner member; means inter-engaging between the members in one position of the members and adapted to retain the jaws in spread apart relation; and stop means limiting movement in opposite directions of the inner member relative to the outer member, said L-shaped jaw having a gripping portion shaped like and in symmetrical balance with the fixed jaw and terminating at its free end in engagement with the free end of the fixed jaw.
